SWITCH AND CORD SET

Walter B. Ford II, Grosse Pointe, Mich.
Application July 17, 1957, Serial No. 46,976

Term of patent 14 years
(Cl. D26—13)

Fig. 1 is a perspective view of a switch and cord set, showing my new design;

Fig. 2 is a fragmentary front elevational view;

Fig. 3 is a top plan view;

Fig. 4 is a fragmentary side elevational view, the opposite side being substantially a mirror image thereof, and

Fig. 5 is a fragmentary cross-sectional view thereof, taken on line 5—5 in Fig. 2.

The dominant features of my new design are shown in solid lines, portions of the cord being broken away in Figs. 2, 4 and 5 for convenience of illustration. Broken line showings of legible matter are for illustrative purposes only.

I claim:

The ornamental design for a switch and cord set, as shown and described.
